MINING MACHINE

Ernst Feeder Muller, Columbus, Ohio, assignor
to The Jeffrey Manufacturing Company,
Columbus, Ohio, a corporation of Ohio

Application January 10, 1930. Serial No. 419,906

28 Claims. (Cl. 262—28)

The present invention relates to that type of mining machine comprising generally a base adapted to be moved about the passages of a mine and having mounted thereon a horizontally projecting cutter bar swingable from side to side of the machine across its front. Ordinarily, machines of this type are mounted on truck wheels adapted to engage the rails of tracks laid along the mine passages. Powerful motor operated devices are provided on the base for slowly swinging the cutter bar from side to side to cut an arcuate kerf in a mine face in advance of the machine or to make a sumping cut in a face parallel to the mine track.

The cutter bar of such a machine has a considerable overhang as regards its supporting base so that the machine as a whole is of large overall length when the cutter bar is positioned to project in front of the machine as it must when the machine is to be moved from one place to another in the mine. The passages through which the machine must travel are often of a winding nature and frequently to enable the machine to negotiate a sharp turn the cutter bar must be angularly adjusted relative to the supporting base.

With the mechanism ordinarily provided for effecting the working swing of a cutter bar, considerable time is wasted in effecting this mere adjusting movement of the bar. According to the present invention, I provide means for rapidly adjusting the bar during the transit of the machine so that the waste of time ordinarily incident to this operation is eliminated. In as much as very little power is required to effect this idle swinging of the bar, the swinging instrumentalities, according to the invention, are of relatively light construction. In order to prevent damage to them in case the cutter bar meets with unexpected resistance, I provide means to relieve the driving parts of strain when such condition arises.

In addition to these general features, the invention includes various details of structure as will appear from the following description of an illustrative embodiment of the invention as shown in the accompanying drawings, wherein:

Figure 1 is a plan view of a machine embodying the present invention.

Figure 2 is a bottom view of a turn-table element of the machine of Figure 1.

Figure 3 is an enlarged view of a portion of Figure 2.

Figure 4 is a section on line 4—4 of Figure 3.

Figure 5 is a view on line 5—5 of Figure 3.

Figure 6 is a section on line 6—6 of Figure 2.

Figure 7 is an enlarged view of control mechanism as appearing in Figure 1, and

Figure 8 is a section on line 8—8 of Figure 2.

Referring now to the drawings, reference numeral 10 denotes a wheel mounted truck whose wheels, not shown, are adapted to engage the rails of the mine track to support the machine. An electric motor 11 supported on the truck through suitable gearing is adapted to drive cable reel 12, the truck wheels, and through screw devices 13, 14 and 15, is arranged in vertical housings 13, 14 and 15, is adapted to vertically adjust or tilt a turn-table 16 mounted on the forward part of the truck for angular adjustment relative to the latter about a vertical axis. Journalled in a bearing 17 formed in the turn-table, see particularly Figure 8, is a vertical shaft 18 to whose upper end is keyed a cutter chain drive sprocket 19. Sprocket 19 engages a cutter chain 20 which travels about an elongated horizontally projecting cutter bar 21 carried by a cutter bar support 22 fixed to turn-table 16.

To the lower end of shaft 18 is keyed a master bevel gear 23 to the hub of which is fixed an eccentric 24 surrounded by an eccentric strap 25. The eccentric strap has a pair of integral lugs 26 and 27 provided with registering bores having an axis lying in a plane at right angles to the axis of shaft 18. Pivoted to lugs 26 and 27 by means of a bolt 28 is a link 29 to whose other end, through a pin 30 at right angles to the plane of bolt 28, is pivoted a pawl carrier 31 carrying a spring-pressed pawl 32 adapted to be oscillated about the axis of a shaft 33 for cooperation with a ratchet wheel 34 fixed on shaft 33. A spring-pressed pawl 35 mounted on the turn-table cooperates with ratchet wheel 34 to prevent reverse rotation of the latter. A shield 36 manipulatable through a control lever 37 is provided for controlling the effective throw of pawl 34 under the drive of eccentric 24, in the well known manner.

To the lower end of pin 30 is secured a block 38 guided in a slot 39 of a plate 40 which is in fixed connection with turn-table 16.

Cut in one end of shaft 33 is a worm 41, Figure 2, engaging a worm wheel 43 which through suitable clutch mechanism is adapted to rotate a drum 44 mounted on a vertical axis on the top of turn-table 16, Figure 1.

Drum 44 has secured to it one end each of cables 45 and 46 whose other ends are trained in opposite directions about sheaves 47 on the turn-table and secured to fixed lugs 48 and 49 respectively. Upon rotation of drum 44, one of the cables will be wound in and the other paid out with

the same speed to swing turn-table 16 in the desired direction. The driving power for the cutter bar swinging and operating mechanisms, is derived from a reversible electric motor 50 mounted on turn-table 16 and having an armature pinion 51 engaging master gear 23.

The elements and combination of elements thus far described are known in the art and per se form no part of the present invention.

10 Mounted adjacent the turn-table periphery and slidable on a line secantial thereto on guides 52 and 53, is an elongated block 54 housing a compression spring 55. Passed through an aperture 56 in an end wall of block 54 is a pin 57 having a head 58 on which one end of spring 55 is seated. The other end of pin 57 bears against an abutment 59 of the turn-table. In the other end of spring 55 is engaged a pin 60 having a head 61 interposed between the end of the spring and the other end 62 of block 54. Threaded in a bore formed in a wall 63 integral with guide 53 is a cap screw 64 whose inner end passes through an aperture formed in end 62 of block 54 to abut head 61 of pin 60. Ordinarily, block 54 occupies the position shown in Figure 4, that is, with its ends equally spaced from abutment 59 and wall 63.

Projecting downwardly of block 54 and secured thereto by any suitable means, as by welding, is a stud 65 on which is journaled the boss 66 of a bell crank lever 67. At one end of the lever on a pin 68 is mounted a double ended pawl 69, while to the other end of the lever is pivoted a link 70 by means of a pin 71. The other end of link 70, Figure 2, is pivoted to an integral ear 72 of eccentric strap 25 by means of a pin 73. An internally toothed ring or ring segment 74 is fixed to the under, non-rotatable support 74' of turn-table 16 in concentric relation with the turn-table axis and in position to be engaged by one end or the other of pawl 69.

On the lower reduced end 65' of stud 65 is pivoted an arm 75 which is held in place by means of a washer 76 and cap screw 77. A boss 78 is formed at the distal end of arm 75 and is provided with a bore in which is rotatable a pin 79 having a head 80. Head 80 is provided with a bore through which is passed a rod 81 pivoted at one of its ends to pawl 69 by means of a pin 82. At its other end, rod 81 has threaded thereon a nut 83 and interposed between this nut and head 80 of pin 79 is a compression spring 84, while interposed between head 80 and pawl 69 is a compression spring 85. Pivot pin 82 being removed from the pawl mounting pin 68, it will be evident that by a suitable movement of arm 75 pawl 69 may be swung to bring either of its ends into operative engagement with the teeth of ring segment 74.

80 A bar 86 is pivoted at one end to arm 75 through pin 79. The opposite end of the bar is guided by a cleat 87 and has pivoted to its extremity a link 88 whose other end is pivoted to a pin 89 fixed in a block 90 in eccentric relation to a shaft 91 likewise fixed in block 90. Shaft 91 is surrounded by a sleeve 92 projecting above turn-table 16 and mounted in a boss 93 of the latter. Revoluble on the upper end of sleeve 92 is a sheave 47 while intermediate the sheave and turn-table is a spacing washer 94 fixed to the turn-table, as by welding, and provided with an axial groove in which is engaged a pin 95 fixed in sleeve 92 to prevent rotation of the latter.

85 Mounted on the lower reduced extremity of sleeve 92 is a roller 96 for cooperation with the circular under support 74'. Fixed to the upper extremity of sleeve 92 is a segmental plate 97 over

which is movable a lever 98 fixed to the upper end of shaft 91. The free end of lever 98 is provided with a boss 99 in which is slidable a pin 100 secured at its upper end to a cap 101. The lower end of pin 100 is urged in the direction of plate 97 by means of a compression spring 102 bearing against the top of boss 99 and a stop 103 on pin 100. Plate 97 is provided with an aperture 97' adapted to be engaged by the lower end of pin 100 and the plate is also provided with a pair of abutment lugs 104 and 105.

88 It will be evident that by rocking shaft 91 through movement of lever 98, arm 75 will be rocked through link 88 and bar 86, thereby moving pawl 69 to engage either one of its ends with the teeth of ring 74 or to disengage the pawl from the teeth. When pin 100 is engaged in aperture 97' the pawl is held in the neutral position shown in Figure 3. Swinging movement of lever 98 in either direction from the neutral position is limited by stop 104 and 105.

90 Shaft 18 is rotated from the motor at a relatively high speed and through the eccentric strap and link 70 causes rapid oscillation of bell-crank 67 and pawl 69 so that when the latter is engaged with the teeth of ring 74, the turn-table will be swung at a relatively rapid rate about its axis so that the mining machine may be transported without interruption through the mine passages.

95 Spring 55 is of sufficient force to resist the normal driving reaction of pawl 69. Should the cutter bar strike the mine wall or any other obstacle and thus throw a greater strain on the operating parts, spring 55 will yield under the abnormal reaction of pawl 69 so that breakage of the parts will be avoided.

100 It will be understood that the described embodiment of my invention is intended to be merely illustrative and that I do not limit myself except as in the following claims.

115 I claim:

1. In a machine of the class described, a base frame movable about a mine, a vertical rotatable shaft on said base frame, means for rotating said shaft, a cutter bar supported on said base frame for swinging movement relative thereto in a horizontal plane, an eccentric on said shaft and rotatable therewith, a pair of intermittent grip devices each having its driving element driven from said eccentric, means driven from the driven element of one of said devices for swinging the cutter bar at a relatively slow working speed, and means driven from the driven element of the other of said devices for swinging said cutter bar at a relatively rapid adjusting speed.

120 2. In a machine of the class described, a base frame movable about a mine, a cutter bar supported on said base frame for swinging movement relative thereto about a vertical axis, a ring-shaped toothed member concentric with said axis and fixed to said base frame, a pawl mounted in connection with said cutter bar and co-operable with the teeth of said toothed member; means for driving said pawl to swing the cutter bar at a relatively rapid adjusting speed, and other means for swinging said cutter bar at a relatively slow working speed.

125 3. In a machine of the class described, a base frame movable about a mine, a cutter bar supported on said base frame for swinging movement relative thereto about a vertical axis, a ring-shaped toothed member concentric with said axis and fixed to said base frame, a pawl mounted in connection with said cutter bar and co-operable with the teeth of said toothed member; means

for driving said pawl to swing the cutter bar at a relatively rapid adjusting speed, and other means driven from the pawl driving means for swinging said cutter bar at a relatively slow working speed.

5 4. In a machine of the class described, a base frame movable about a mine, a cutter bar supported on said base frame for swinging movement relative thereto about a vertical axis, a ring-shaped toothed member concentric with said axis and fixed to said base frame, a pawl cooperable with the teeth of said toothed member, a mounting for said pawl in connection with said cutter bar, means for driving said pawl to swing the cutter bar, and means supporting the mounting against normal reaction of the pawl but yieldable under abnormal reaction thereof due to resistance of the cutter bar to swinging movement.

10 5. In a machine of the class described, a base frame movable about a mine, a cutter bar supported on said base frame for swinging movement relative thereto about a vertical axis, a ring-shaped toothed member concentric with said axis and fixed to said base frame, a pawl cooperable with the teeth of said toothed member, a block on which said pawl is mounted, a guide for said block in connection with the cutter bar and in which the block is slidable in the reactional direction of the pawl, a spring between said block and an abutment in fixed connection with the cutter bar to oppose normal reaction of said pawl, and means for driving said pawl to swing the cutter bar relative to the base frame.

15 6. In a machine of the class described, a base element movable about a mine, a turn-table element mounted on said base element for angular adjustment relative to the latter about a vertical axis, a cutter bar secured to said turn-table, a ring-shaped toothed member fixed to one of said elements concentric with said axis, a pawl mounted on the other of said elements for cooperation with the teeth of said toothed member, means for driving said pawl to rotate the turn-table element relative to the base element, and means driven by the pawl driving means to rotate the turntable at a speed slower than that effected by said pawl.

20 7. In a machine of the class described, a base element movable about a mine, a turn-table element mounted on said base element for angular adjustment relative to the latter about a vertical axis, a cutter bar secured to said turn-table, a ring-shaped toothed member fixed to one of said elements concentric with said axis, a pawl cooperable with the teeth of said toothed member, a mounting member for said pawl on the other of said elements, means for driving said pawl to rotate the turn-table, and means supporting the mounting member against normal reaction of the pawl but yieldable under abnormal reaction thereof.

25 8. In a machine of the class described, a base element movable about a mine, a turn-table element mounted on said base element for angular adjustment relative to the latter about a vertical axis, a cutter bar secured to said turn-table, a ring-shaped toothed member fixed to one of said elements concentric with said axis, a pawl mounted on the other of said elements for cooperation with the teeth of said toothed member, means including a motor on the turn-table element for driving said pawl to rotate the turn-table element relative to the base element in either direction, and motor driven mechanism operable to propel the base element, said pawl driving means

being operable independently of said motor driven mechanism.

9. In a machine of the class described, a base element movable about a mine, a turn-table element mounted on said base element for angular adjustment relative to the latter about a vertical axis, a cutter bar secured to said turn-table, a ring-shaped toothed member fixed to one of said elements concentric with said axis, a pawl cooperable with the teeth of said toothed member, a mounting member for said pawl on the other of said elements, means including a motor on the turn-table element for driving said pawl to rotate the turn-table, and means supporting the mounting member against normal reaction of the pawl but yieldable under abnormal reaction thereof.

10 10. In a machine of the class described, a base frame movable about a mine, a turn-table mounted on said frame for angular adjustment relative to the latter about a vertical axis, a cutter bar secured to said turn-table, an internally toothed ring fixed to the frame concentric with said axis, a double-acting pawl mounted on the turn-table for selective cooperation with the teeth of said ring, means for driving said pawl to rotate the turn-table, and means driven by the pawl driving means to rotate the turn table in either direction at a speed slower than that effected by said pawl.

15 11. In a machine of the class described, a base frame movable about a mine, a turn-table mounted on said frame for angular adjustment relative to the latter about a vertical axis, a cutter bar secured to said turn-table, an internally toothed ring fixed to the frame concentric with said axis, a double-acting pawl mounted on the turn-table for selective cooperation with the teeth of said ring, and means including a motor on the turn-table for driving said pawl to rotate the turn-table.

110 12. In a machine of the class described, a base frame movable about a mine, a turn-table mounted on said frame for angular adjustment relative thereto about a vertical axis, an internally toothed ring fixed to the frame concentric with said axis, a block mounted on said turn-table for sliding movement on a secantial line adjacent the turn-table periphery, yieldable means interposed between the ends of said block and stops on the turn-table, a double-acting pawl pivoted on said block, means for selectively engaging said pawl with the teeth of said ring, and means for driving said pawl to rotate the turn-table, said yieldable means being yieldable only under abnormal reaction of the pawl.

115 13. In a machine of the class described, a base frame movable about a mine, a turn-table mounted on said frame for angular adjustment relative thereto about a vertical axis, an internally toothed ring fixed to the frame concentric with said axis, a block mounted on said turn-table for sliding movement on a secantial line adjacent the turn-table periphery, yieldable means interposed between the ends of said block and stops on the turn-table, a double-acting pawl pivoted on said block, means for selectively engaging said pawl with the teeth of said ring, and means including a motor on the turn-table for driving said pawl to rotate the turn-table, said yieldable means being yieldable only under abnormal reaction of the pawl.

14. In a machine of the class described, cutter bar swinging means including a ball-crank lever, a double-ended pawl pivoted on said lever, an arm pivoted to said lever on an axis parallel

- to that of the pawl, a rod pivoted at one end adjacent one end of the pawl and having an abutment at its opposite end, said arm being provided with means slidably engaging an intermediate portion of said rod, a spring interposed between the arm and pawl, a spring interposed between the arm and abutment, and means for swinging the arm to adjust the pawl. 20. In a machine of the class described, the combination with a portable base frame, of a turntable mounted thereon for angular adjustment relatively thereto about a vertical axis, a cutter-bar mounted on said turntable to move bodily therewith, an internally toothed ring fixed to the base frame concentric with said vertical axis, a double acting pawl mounted on a vertical axis on the turntable for selective cooperation with the teeth of said ring, and means for driving said pawl to rotate the turntable in one direction when the pawl is in one position and in the opposite direction when the pawl is in another position. 21. In a machine of the class described, the combination with a portable supporting frame, of a turntable mounted thereon, a cutter-bar secured to said turntable to swing bodily therewith, means for operating said cutter-bar including the feed thereof by slow swinging of said cutter-bar, an arcuate rack concentric with the axis of swinging movement of said turntable, means comprising a double acting pawl associated with said rack for effecting rapid swinging movement of said turntable and said cutter-bar in either direction, manually operated mechanism for setting said pawl to effect swinging of the cutter-bar in either direction, and motor driven mechanism operable to propel said supporting frame, said pawl being operable independently of said motor driven propulsion mechanism. 22. In a machine of the class described, the combination with a base frame movable about in a mine, of a kerf-cutter supported on said base frame relatively thereto on an upright axis, an arcuate toothed member concentric with said upright axis and fixed to said base frame, means comprising a pawl associated with said arcuate toothed member for swinging the kerf-cutter at a relatively rapid adjusting speed, other means for feeding said kerf-cutter at a relatively slow working speed, and mechanism common to the fast swinging means and the slow swinging means for driving either one or the other. 23. In a machine of the class described, the combination with a supporting frame, of a cutter-bar mounted thereon for swinging movement relatively thereto, and mechanism comprising a yieldable fulcrum for swinging said cutter-bar. 24. In a machine of the class described, the combination with a supporting frame, of a cutter-bar mounted thereon for swinging movement relatively thereto, a stationary arcuate rack, a pawl associated with said rack, means comprising a fulcrumed oscillatable member for reciprocating said pawl to secure swinging movement of said cutter-bar and shock absorbing means associated with said fulcrum to permit the latter to yield when said cutter-bar meets an obstruction. 25. In a machine of the class described, the combination with a supporting frame, of a cutter-bar mounted thereon for swinging movement relatively thereto, an arcuate rack concentric with the axis of swinging movement of said cutter-bar, means comprising a pawl associated with said rack and a pivoted oscillatable device connected to said pawl for effecting swinging of said cutter-bar, a support for the pivot of said oscillatable device, means for mounting said support for sliding movement on a secantial line relative to said arcuate rack, and yieldable means interposed between said support and said mounting means to relieve abnormal reaction on said pawl.
- 5 10 15 20 25 30 35 40 45 50 55 60 65 70 75 80 85 90 95 100 105 110 115 120 125 130 135 140 145 150
17. In a machine of the class described, a base element movable about a mine, a turntable element mounted on said base element for angular adjustment relative to the latter about a vertical axis, a cutter-bar secured to said turntable, a ring-shaped toothed member fixed to one of said elements concentric with said axis, a pawl mounted on the other of said elements for cooperation with the teeth of said toothed member, means for driving said pawl to rotate the turntable element relative to the base element, and means driven by the pawl driving means to rotate the turntable at a speed slower than that effected by said pawl. 18. In a machine of the class described, a base element movable about a mine, a turntable element mounted on said base element for angular adjustment relative to the latter about a vertical axis, a cutter-bar secured to said turntable, a ring-shaped toothed member fixed to one of said elements concentric with said axis, a pawl cooperable with the teeth of said toothed member, a mounting member for said pawl on the other of said elements, means for driving said pawl to rotate the turntable, and means supporting the mounting member against normal reaction of the pawl but yieldable under abnormal reaction thereof. 19. In a machine of the class described, a base element movable about a mine, a turntable element mounted on said base element for angular adjustment relative to the latter about a vertical axis, a cutter-bar secured to said turntable, a ring-shaped toothed member fixed to one of said elements concentric with said axis, a pawl cooperable with the teeth of said toothed member, a mounting member for said pawl on the other of said elements, means including a motor on the turntable element for driving said pawl to rotate the turntable, and means supporting the mounting member against normal reaction of the pawl but yieldable under abnormal reaction thereof.

26. In a machine of the class described, the combination with a supporting frame, of a cutter-bar mounted thereon for swinging movement relatively thereto, an arcuate rack mounted in stationary position on said supporting frame concentric with the axis of swinging movement of said cutter-bar, means comprising a double acting pawl associated with said rack and a pivoted oscillatable device connected to said pawl, and shock absorbing means associated with the pivot of said oscillatable device and mounted on a secantial line relative to said arcuate rack.

5 27. In a machine of the class described, the combination with a supporting frame, a turntable on said frame and a cutter-bar mounted on the turntable for swinging movement therewith, of a stationary arcuate rack on said frame, a double acting pawl associated with said rack, means comprising a bell crank lever for operating said double acting pawl to effect swinging of the cutter-bar in either one direction or the

other, and manually operated mechanism operable from the top of the turntable for positioning the pawl in connection with said rack to effect such swinging of the cutter-bar in either one direction or the other.

10 28. In a machine of the class described, a movable supporting frame, a cutter bar carried by said supporting frame and swingable horizontally relative to the frame, motor driven propulsion mechanism for said frame, and motor driven means comprising a gearing train for swinging said cutter bar at a relatively slow working speed and a gearing train alternatively operable for swinging said cutter bar in either direction at a relatively fast adjusting speed, the operation of said swinging means at adjusting speed being independent of the operation of said propulsion mechanism so that rapid adjustment of the cutter bar is possible during propulsion of the machine along a mine passage.
